UNITED STATES PATENT OFFICE

GLEN C. CARNAHAN, OF CHICAGO, ILLINOIS, ASSIGNOR TO JAMES B. CLOW & SONS,
OF CHICAGO, ILLINOIS, A CORPORATION OF ILLINOIS

GAS-BURNING APPARATUS

Application filed July 12, 1928. Serial No. 292,243.

This invention relates in general to fuel burning devices, and while the principles thereof are capable of use in various apparatus, I have shown the invention herein for 5 illustrative purposes as incorporated in a gas burning heating apparatus.

An apparatus of this character includes a combustion chamber and if the pilot light should become extinguished, it is customarily 10 manually relighted from the front of the apparatus. Should there be an accumulation of gas in the combustion chamber, the lighting of the pilot light will produce an explosion of greater or less intensity, depending 15 upon the amount of gas accumulated in the chamber. Explosions thus produced have in some instances caused the flame to shoot out of the front opening of the chamber with unfortunate results to the person relighting 20 the pilot.

One of the primary purposes of my present invention is to provide for relief of the pressure produced in the combustion chamber by such an explosion so as to prevent the 25 flames from issuing at the front of the furnace and causing injury to the operator.

Other objects and advantages of this invention will be apparent as the same becomes better understood from reference to the following description when considered in connection with the accompanying drawings, the 30 single figure of which is a vertical sectional view through a heating apparatus equipped with my invention.

Referring to the drawings more in detail, 35 reference character 5 indicates the base of a fuel burning apparatus above which is disposed the combustion chamber 6 formed by the bottom wall 7, the front and rear end 40 walls 8 and 9 respectively, and the side walls (not shown).

Within the combustion chamber is mounted one or more burners 11 supplied with a combustible mixture from the mixer 12 and 45 ignited by a pilot burner 13 which heats a thermostatic element 14 controlling a shut-off valve in the chamber 15 disposed in the gas supply pipe 16. The construction thus far described forms the subject matter of my 50 copending applications, Serial No. 290,895,

filed July 7, 1928, and Serial No. 290,896, filed July 7, 1928.

While the extinguishment of the pilot light results in shutting off the gas supply to the main burners, a small amount of gas will continue to escape into the combustion chamber from the pilot burner, and if this continues for some time, a considerable quantity of gas may accumulate in the combustion chamber. When the operator introduces a flame 60 through the opening 16 above the pilot burner to relight the same, this gas in the combustion chamber will be ignited and an explosion will result.

To obviate danger to the operator, the 65 combustion chamber is provided with a relief device in the form of a swinging door or flap 17 suspended from a pivot or pivots 18 at the rear end of the combustion chamber. The lower edge of this door normally 70 rests under the influence of gravity against the outer edge of a flange or ledge 18 so that the opening is completely closed.

In the event of an explosion, however, the 75 door will swing outwardly and upwardly into the dotted line position shown, affording a relief for the pressure generated within the combustion chamber so that the flame is not blown out through the front of the chamber.

The opening 16 in the front wall of the 80 chamber is shielded by a pivoted door or shield 19 suspended from the pivot or pivots 21 so that it may be swung inwardly and upwardly when desired for access to the interior of the chamber, but normally it assumes the position shown on the drawings and in the event of an explosion in the 85 chamber will be forced into this position so as to prevent in a very large measure flames from issuing at the front of the apparatus. 90

It should be apparent from the foregoing that in the event of an explosion the flames will be prevented from shooting out the front of the furnace and burning the operator, and the pressure in the combustion chamber will be relieved by the door or flap 17 at the rear 95 of the apparatus where flames, if they should issue, can do no harm.

The structural details illustrated and described may obviously be varied within con- 100

siderable limits without departure from the essence of the invention as defined in the following claim.

I claim:

- 5 A fluid fuel burning apparatus comprising a walled combustion chamber including front and rear walls, means for burning fluid fuel in said chamber, the front and rear walls each having an opening therethrough, a pivotally mounted door for normally closing said opening in the rear wall and opening outwardly from said chamber, and a door normally closing said opening in the front wall of said chamber and pivotally mounted for swinging inwardly only of said chamber.
- 10
- 15

In witness of the foregoing I affix my signature.

GLEN C. CARNAHAN.
